UNITED STATES PATENT OFFICE.

GEORGE M. DILLON AND JAMES H. BEVINGTON, OF BELLEVUE, OHIO.

HEAD-REST.

SPECIFICATION forming part of Letters Patent No. 380,252, dated March 27, 1888.

Application filed October 22, 1887. Serial No. 253,115. (No model.)

To all whom it may concern:

Be it known that we, GEORGE M. DILLON and JAMES H. BEVINGTON, citizens of the United States, residing at Bellevue, in the county of Huron and State of Ohio, have invented certain new and useful Improvements in Combined Head - Rest and Book - Supporter, of which the following is a specification.

The object of our invention is to provide an article which will support the head, and by the addition of a small piece of steel or other suitable material will also hold a book in a position so that it can be read while the traveler is using the head-rest. It is also made so that it can be taken apart and put up in a small space, and is especially constructed so as to be cheap and durable.

This invention consists of a piece of steel spring which is provided with adjustable ends which slide back and forth upon the middle piece as it is desirable to adjust the height of the rest. The end pieces are provided with holders at their ends, which allow of their grasping and holding two extended arms or bars, over which is placed and sewed a piece of plush, leather, or any suitable or desirable material, which forms a convenient and easy resting-place for the head. The middle piece of steel is provided at or near its center with a slit which is wide enough to permit of its being slipped over the seat - back arm or striker-arm, so that it will be in a convenient position for the head to rest upon.

The book-holder consists of a clamp for holding the book and an adjustable arm pivoted to said clamp, and having a clamp for securing it to the edge of the head-rest, as herein-after fully described. This device may also be employed as a card-table or a lunch-table, and suitable bracers consisting of wooden strips may be arranged from side to side of the device, and they may be so attached that when the spring-support is loosened and removed the said strips may be rolled up with the plush cover and packed away.

Referring to the accompanying drawings, which form a part of this specification, Figure 1 is a general perspective view. Fig. 2 is a detail perspective view with the book-rest removed. Fig. 3 is a bottom view of the head-rest with a portion broken away, showing the manner of securing the wooden strips in place.

In these drawings, A represents a seat-back arm or striker-arm, to which is attached my improved head-rest and book-holder.

C represents the plush, leather, or other suitable material, which extends across the bars or arms D D and which serves as a head-rest. These bars D D are provided near their center with two projections, E, which prevent the ends of the steel-spring supports S S' from slipping farther down and tearing the plush, leather, or other covering which constitutes the head-rest. One end of each of the said steel springs S S' is, as above stated, made so that it will slip down or up on the middle piece, T. The latter is provided with the slit F, for allowing it to be attached to the seat-back arm or striker-arm A to allow the height of the head-rest to be adjusted. The other ends are bent down and then turned upward, so as to form hooks or pockets for the extending arms or bars D D, which fit in between the projections E.

The clamp, before referred to, which holds the book is composed of two pieces, B B', of spring-steel or other suitable material, which have their lower ends bent approximately at right angles and riveted together at b in such a manner as to leave a slight space between their vertical ends for the insertion of a book. The lower end of the piece B', however, has an extension-arm, G, which is pivoted to a second arm, J, having one end bent up, so as to form a clamp, H, which engages the edge of the plush cover and the bar D, and at this same end of the arm J is pivoted, at j, a supporting-arm, K, which bears upon the under side of the cover c, and against which the latter and the bar D are pressed by the clamp H. One end of the book may be placed between the clamp-pieces B B', which will prevent the leaves from turning voluntarily, while the other end of the book may be held in the hand of the reader and the apparatus adjusted to suit by virtue of the pivoted arms.

The sides of the slit F are provided with insulators F', of any suitable material, to prevent it from scratching the seat-back arm or striker-arm A.

As before mentioned, when the device is to be employed as a table, the plush cover is provided with supporting - strips L, which are placed under the cover and have their ends

secured in pockets formed in the edges of the former by turning a portion of the same under and stitching, as at *o*, between the slats or supports, as shown in Fig. 3.

5 Having thus described our invention, what we claim as new therein, and desire to secure by Letters Patent, is—

1. The combination, with the cover and the bars secured at two sides thereof, of the steel 10 springs *S S'*, attached to said bars, and the spring *T*, provided with a slot and being adjustably secured to said springs *S S'*, substantially as set forth.

2. The combination, with the head-rest, substantially as described, of a book-rest consisting of a clamp for holding the book, having an adjustable arm, and a clamp securing said arm to the head-rest, substantially as described. 15

3. The combination of the head-rest, constructed substantially as shown and described, 20 and the book-holder made removable therefrom and adapted to be attached to the head-rest, as and for the purposes set forth.

4. The combined head-rest dining or card table provided with a plush or other cover 25 and having means for attachment to the seat-back arm, and provided with wooden strengthening-pieces extending from side to side, and which are adapted to be rolled up with the cover when desired.

G. M. DILLON.
